(57) **CLAIM**

The ornamental design for a demolition hammer head, as shown and described.

DESCRIPTION

FIG. 1 is a rear perspective view of the demolition hammer head.

FIG. 2 is a side elevation view thereof.

FIG. 3 is a side elevation view opposite to that of FIG. 2.

FIG. 4 is a top plan view thereof.

FIG. 5 is a bottom plan view thereof.

FIG. 6 is a front elevation view thereof.

FIG. 7 is a rear elevation view thereof; and,

FIG. 8 is front perspective view thereof.

The broken lines in the drawings illustrate features of the demolition hammer head that form no part of the claimed design.
